UNITED STATES PATENT OFFICE.

GEORGE A. WILLIAMS, OF WATERBURY, CONNECTICUT, ASSIGNEE TO THE WILLIAMS SEALING CORPORATION, OF WATERBURY, CONNECTICUT, A CORPORATION OF CONNECTICUT.

BOTTLE-CAP.

1,108,959.

Specification of Letters Patent. Patented Sept. 1, 1914.

Application filed September 30, 1912. Serial No. 723,077.

To all whom it may concern:

Be it known that I, GEORGE A. WILLIAMS, a citizen of the United States, residing at Waterbury, in the county of New Haven and State of Connecticut, have invented a new and useful Improvement in Bottle-Caps, of which the following is a specification.

This invention relates generally to bottle caps and more particularly to certain improvements upon the bottle cap patented to me December 10, 1907, No. 873,646.

The object of the present invention is to improve the construction of cap and lever covered by the patent referred to, said improvements consisting in arranging a bearing sleeve fixed in its position and avoiding the tendency to roll, and the improvement consists also in so constructing the lever that at the completion of its locking operation it will snap into position with the handle against the side of the bottle and the head of the lever beneath the ends of the contracting ring, the curved portion of the lever head bearing against the bearing sleeve which as previously stated is stiffened in order to render its position absolutely fixed.

The invention also embraces certain details of construction hereinafter fully described, and pointed out in the claims.

In the drawings forming a part of this specification: Figure 1 is a side view of a bottle cap embodying my improvements, said cap being applied to a bottle and locked thereon. Fig. 2 is a detail perspective view showing a portion of the cap and illustrating the manner of stiffening and fixing the position of the bearing sleeve. Fig. 3 is a face view of the cap, the bearing sleeve being shown in section. Fig. 4 is an end view of the fastening lever, and Fig. 5 is a face view taken from the rear. Fig. 6 is a rear view showing the crimp in rear part of ring.

In making my improved bottle cap I make the cap portion A, and slotted portion A', substantially the same as heretofore. The bearing sleeve B, however, which is arranged at the front of the slotted portion is constructed with flattened ends C, upon the upper side thereof, the flattening operation

being accomplished by the proper shaping of the dies for shaping the bearing sleeve B. The clamping ring D, is of the usual construction and is provided with the usual hooked end D' which are engaged by the curved and converging sides of the head of the lever E, and it will be noted that the inner or central member E' is curved inwardly or rearwardly a certain distance as shown in Fig. 4, the purpose of said inward or rearward curve being to throw this member beneath the hooked members D', as most clearly shown in Fig. 1, and by reference to Fig. 5 it will be noted that the converging sides are spread slightly as shown at E' so that when the lever is thrown down to its locked position as shown in Fig. 1, the ends of the clamping ring can have a slight outward or expanding movement simultaneous with the snapping of the member E', thereby beneath thus locking the lever and holding the same firmly against the bearing sleeve B. A quick and easy opening or unfastening of the cap however is not interfered with. Heretofore there was a slight tendency of the bearing sleeve to roll upwardly incidental to the rapid opening and closing of the lever, and this rolling up of the bearing sleeve tended to take it away from the lever and thereby allow the lever to lay obliquely instead of a vertical position but by stiffening the ends of the bearing sleeve by flattening the same this tendency to roll is completely avoided, consequently the position of the bearing sleeve with relation to the curved head of the lever is fixed and the vertical position of the lever is thereby maintained. It will thus be seen that I provide an improved construction of bottle cap which will accomplish the objects hereinbefore referred to.

In Fig. 6 I have shown the ring D with a central crimp D' at the rear thereof which holds the ring against shifting or lateral movement and thereby holds the hooked ends of said ring directly beneath the center of the bearing sleeve when the lever is locked, and thus always holds the lever in proper position against the bearing sleeve.

What I claim is:—

1. A bottle cap comprising a slotted apron,

bearing sleeve, contracting ring and lever, the ends of the bearing sleeve being flattened to prevent rolling, said ring having a crimp.

2. A bottle cap having a slotted apron, 5 bearing sleeve, with flattened ends, a contracting ring with hooked ends and a lever having converging sides adapted to engage said hooked ends and also bear against said

sleeve, the inner end of said lever head being curved to engage the under side of said 10 hooked ends when said lever is turned down.

GEORGE A. WILLIAMS.
